UNITED STATES PATENT OFFICE.

JACOB HINZ, JR., OF WHITE LAKE, SOUTH DAKOTA.

ARTIFICIAL HAND.

No. 861,982.

Specification of Letters Patent.

Patented July 30, 1907.

Application filed April 15, 1907. Serial No. 368,238.

To all whom it may concern:

Be it known that I, JACOB HINZ, Jr., a citizen of the United States, residing at White Lake, in the county of Aurora and State of South Dakota, have invented a new and useful Artificial Hand, of which the following is a specification.

This invention relates to an artificial hand for the use of those persons who have lost by accident or otherwise their natural hand but not the entire fore-arm.

10 The object of the invention is to improve generally the construction of artificial hands; to provide an articulated lever therefor to serve as a thumb which may be kept normally closed against the hand and opened at will or which may be held in an open position and 15 closed when desired; to provide means for securely locking the thumb lever in closed position against the hand; and for other novel combination and arrangement of parts hereinafter described and definitely claimed.

In the accompanying drawings: Figure 1 is a perspective view of one side of the artificial hand. Fig. 2 is a 20 similar view of the opposite side.

Similar numerals of reference indicate the same parts on all the figures.

The artificial hand of the present invention comprises the hand proper 1, forearm socket 2, elbow pad 3 and upper arm band 4, the latter consisting of a broad strip of leather 5 sufficiently long to embrace the arm and secured thereto by a plurality of straps 6 on one end fastened to buckles 7 on the opposite end, as clearly 30 shown on the drawing. Other fastening devices may be used if desired, but straps and buckles have proven very satisfactory and are preferred.

Connected to the arm band 4 in a convenient position by links 8 and 9 is the elbow pad 3 also made of leather by preference; narrow strips 10 and 11 extend from the edge of the elbow pad to form loops which are fastened to the links 8 and 9, thereby forming a flexible connection between the band 4 and the elbow pad. At the bottom of the arm band 4 are secured two strips 40 12, 13 of metal, the former strip 12 having upwardly extending projections 14 and 15 in which the links 8 and 9, respectively, are pivoted. The metal strip 13 also has an upward extension 16 to which is hinged a link 17 for a purpose hereinafter described.

45 The forearm socket 2 is made on a skeleton metal frame comprising a longitudinal member 18 integral with or rigidly attached to an approximately circular end plate 19 that forms the lower or wrist end of the socket 2. At the upper and lower ends of the member 50 18 are oppositely extending transverse metal bands 20 and 21 respectively, which are shaped to conform substantially to the transverse curvature of the forearm. On the opposite side of the socket 2 is a second longitudinal member 22 hinged to a lug 23 on the end plate

19, provided with transverse curved metal bands 24 55 and 25. Riveted to the transverse bands 21, 22 is a lining sheet 26 of leather or other suitable material, extending the full length of the socket, and around three sides thereof. A second lining sheet 27 riveted to the metal bands 24, 25 and of equal length, covers 60 the remaining side of the socket 2 and overlaps the edges of the sheet 26. The edges of the sheet 27 are provided with eyelets 28 or lacing hooks for a lace 29, by means of which the edges of the sheet are drawn toward each other and the socket 2 fastened to the 65 stump of the wearer's forearm. The lower end of the cover sheet 27 below the metal band 21 is a little wider than that portion immediately above it and is drawn together by a separate lacing 30.

Projecting forwardly from the end plate 19 is a stem 70 31, rigidly attached to said plate, its outer end 32 being flattened and crooked in the semblance of a partially flexed hand and at its extreme end, divided into two parallel fingers 33. The upper portion of the stem 31 near the plate 19 is screw threaded at 34 and provided 75 with a circular nut 35 milled on its edge, which may be rotated by the fingers. Extending through a slot 36 in the stem 31 immediately below the "hand" 32, is a "thumb" 37 articulated on the stem by a pin 38 and long enough to pass when closed between the fingers 33. 80 The opposite end of the thumb 37 has pivoted thereto one end of a connecting link 39, to which is pivoted in turn a short straight bar 40, extending back on one side of the socket 2 to near the metal band 21, at which point is a loop 41, pivoted to the bar 40, through which loop 85 a strap 42 runs. In place of the loop 41 a roller may be substituted in a manner well understood. One end of the strap 42 is connected to a coil spring 43 attached to the upper metal band 24; its opposite end is adjustably secured to a buckle 44 on the elbow cap 3. 90

Below the thumb 37 is a short lever 45 fulcrumed within the slot 36 in the stem 31; one end of said lever is pivoted to the connecting link 39 intermediate the ends, while at the opposite end, and close to the stem 31, is journaled a small friction wheel 46. A second 95 short bar 47, on the opposite side of the stem 31 from the bar 40, is pivoted to a bracket 48 rigidly attached to the journal of the friction wheel 46. A loop 49, or roller, on the upper end of the bar 47 receives a strap 50 similar to the strap 42, to one end of which is hooked 100 a coiled spring 51 attached to the upper metal band 20. The other end of the strap is adjustably connected to a buckle 52, attached to the link 17 on the arm band 4 heretofore described. A guide 53 is fastened to the metal band 24 under which the strap 50 passes to the 105 buckle 52 for the purpose of keeping the strap close to the side of socket 2. A similar guide 54 for the strap 42 is placed on the metal band 20. Surrounding the

22

straight rods 40 and 47 are spiral springs 55 and 56 respectively, which bear at one end against pins 57 and 58 in the rods 40 and 47, and at the other end against a flat cross bar 59 securely attached to the stem 31 at its junction with the end plate 19 through which said rods 40 and 47 pass and are guided thereby. The rods 40 and 47 are provided with a plurality of perforations so that the pins 57, 58 may be changed to vary the tension of the spiral springs.

- 10 When the thumb is to remain normally in the closed position, the spring 56 will bear against the cross bar 59, but the spring 55 will be held out of connection with said bar by a pin 60 placed in a hole in the rod 40 as shown in the drawing. When the conditions are reversed and the thumb is to remain open, the spring 55 will press against the cross bar 59 and the spring 56 held out of contact therewith by a pin.

15 The under surface of the "hand" 32 is preferably lined with a piece of leather 61 to afford a better holding surface, and to afford a better grip to the fingers 20 their inner surfaces are provided with cross ribs 33 and grooves 62.

20 When the invention is to be applied, the lacing 29 is loosened and the socket opened, the member 22 it 25 will be remembered having a hinge connection with the end plate. The stump of the forearm is then placed in the socket and securely fastened by the lacing 29 and the leather band 4 strapped around the upper arm, care being taken that the pad 3 comes beneath 30 the elbow. Now by straightening the arm the strap 50 draws the short bar 47 upwardly which, through the connections described, causes the thumb 37 to open for the purpose of grasping some article; then by slightly bending the elbow the thumb closes and securely holds 35 whatever may have been picked up. The spring 56 tending at all times to close the thumb while the spring 51 holds the strap 50 always under tension. Should the spring 55 be placed in operation and the spring 56 prevented from pressing on the bar 59. The thumb 40 will remain normally open and may be closed by bending the elbow which movement draws on the strap 42, and through the connections shown closes the thumb. When it is desired to keep the thumb closed irrespective of the position of the arm, the nut 35 is screwed out- 45 wardly on the stem 31 until it bears against the lever 45 which in turn presses against the closed thumb as represented in Fig. 2.

Having thus described the invention what is claimed is:—

1. An artificial hand comprising a stump socket, a hand 50 projecting therefrom, a thumb articulated to said hand, two rods connected to said thumb, a spring acting on each rod, one spring tending to hold said thumb open and the other to hold it closed against the hand, and independent means for operating each of said rods against the 55 tension of its spring.

2. An artificial hand comprising a stump socket, an upper arm band and a hand rigidly attached to said socket, a thumb articulated to said hand, means attached to the arm band for positively opening said thumb, separate means also attached to the arm band for positively closing said thumb on the hand, a spring attached to the opening means and another spring attached to the closing means, each spring tending to act in opposition to the 60 respective opening and closing means.

3. An artificial hand, having a socket for the arm 65 stump formed of a two part skeleton frame hinged together, each part being separately lined, the lining of one part overlapping that of the other part and a lacing for fastening the edges of the overlapping part.

4. An artificial hand having a socket, a stem projecting therefrom threaded at its upper end and provided with a crooked lower end forming a hand, a thumb lever articulated to said stem, means for opening and closing said lever, and a hand nut on said threaded portion of the 70 stem adapted to lock said thumb in closed position.

5. An artificial hand having a stump socket, a stem projecting from said socket and rigidly attached thereto, said stem having a screw thread thereon, a crooked outer end and a slotted portion between said thread and crooked 80 portion, a thumb lever extending through said slot and articulated to said stem, a draw rod for closing said thumb lever joined thereto by a connecting link, a second lever extending through said slot and connected at one end to said link and at the other end to a second draw rod, 85 independent means for operating each draw rod, and a nut on the threaded portion of said stem.

6. An artificial hand comprising a stump socket, an upper arm band, a stem projecting from the lower end of 90 said socket and having a crooked end separated into fingers, a lever or thumb articulated to said stem and adapted to pass between said fingers, means connected to the upper band for positively opening the thumb lever, a second means attached to said upper band for positively closing said thumb lever, and a separate resilient means 95 for acting in contrary direction to each positively operating means.

In testimony that I claim the foregoing as my own, I have hereto affixed my signature in the presence of two witnesses.
